H. O. RUGH

THERMIONIC VALVE

Filed Nov. 16, 1922

Inventor:
Harry O. Rugh
By G. L. Bragg Atty.

UNITED STATES PATENT OFFICE.

HARRY O. RUGH, OF CHICAGO, ILLINOIS.

THERMIONIC VALVE.

Application filed November 16, 1922. Serial No. 601,304.

My invention relates to wireless systems of electrical communication and has for one object the provision of a current rectifying device or thermionic valve which may be connected with lamp sockets of commercial lighting systems, this device constituting a plug by which wireless receiving equipment may be connected with ordinary commercial lighting circuits in a manner to complete the wireless receiving systems. The current rectifying device is preferably in the form of an incandescent lamp to furnish light while also serving to complete the wireless receiving equipment. The current rectifying device of my invention may form a part of the equipment disclosed in my co-pending application Serial No. 601,305, filed of even date herewith, although the invention is not to be limited to such a use.

The invention has for another of its objects the provision of means whereby the plate, wing, or other current rectifying electrode, that is associated with the filament or other heating element of the rectifying device, may be connected with a selected side of a lighting circuit, it being of advantage to associate such electrode more closely with the ungrounded side of a commercial lighting circuit than with the grounded side thereof in accordance with the present development of the art.

In carrying out the first object of the invention a rheostat is mounted upon the current rectifying lamp and has its resistance in circuit with the lamp filament in order that the generator of the lighting system may replace the battery. The resistance winding of the rheostat is preferably also a choke coil to enable it to eliminate the hum of the generator in a direct current system. The resistance changing lever of the rheostat is accessible for operation from the exterior of the lamp, being preferably pivoted on and desirably projecting into the lamp base wherein the resistance is contained and which base is hollow where the resistance and the inner end of the lever is located to permit of movement of the lever. In order to adapt the lamp to certain wireless receiving systems the base thereof is equipped with two binding posts. One of these binding posts is connected with the rectifying electrode that is adjacent the lamp filament. The other binding post is connected with the lamp contact with which the rheostat is connected.

I will explain my invention more fully by

reference to the accompanying drawing in which Fig. 1 is a longitudinal sectional elevation of the preferred form of rectifying device, some of the circuit relationship of 60 this device being diagrammatically illustrated; and Fig. 2 is a sectional view on line 2-2 of Fig. 1.

Like parts are indicated by similar characters of reference throughout the different 65 figures.

The looped heating element 1 may also constitute a lighting element, being enclosed within a glass bulb 2 as in ordinary incandescent lamp practice. The base 3 of the 70 lamp is preferably metallic and has one end assembled with one end of the lamp bulb, as illustrated. The lamp base carries two contacts 4 and 5 which are preferably in the form of prongs, the contact 4 being connected by the leading in wire 6 with one terminal of the filament 1 and the contact 5 being connected with the other terminal of the filament through the rheostat resistance 7 which is located between the latter contact 75 and the filament and which is connected with the filament by means of another leading in wire 8. The contacts 4 and 5 are carried upon a disc 9 of insulation that is enclosed by the base 3 at its outer end. The contact 80 85 85 is insulated from the base 3 but contact 5 is electrically connected with this base through the intermediation of the conductor 10 which may be soldered to the base at one end and which may be firmly electrically and mechanically assembled with the contact 5 at its other end by means of a nut 11. This nut also serves to assemble the contact 5 with the disc 9. Another nut 12 serves likewise to assemble the contact 4 with said disc. 95

As will more fully hereinafter appear, the contacts 4 and 5 may be connectible with an incandescent lamp socket in a manner to include the lamp filament in bridge of the lighting circuit. The lamp base 3 is hollow 100 between the adjacent end of the lamp bulb and the disc to accommodate the rheostat resistance and the inner end of the resistance changing lever 13 which is mounted upon the resistance carrier 14 and is brought into electrical connection with the metallic lamp base 3 by means of a metallic bracket 15 which is mechanically and electrically connected with the base 3 and with the pivoted lever 13 through the lever pivot 16. 105 The core 17 for the resistance is surrounded by the wire thereof as is understood. This 110

core is made of iron if the rheostat resistance is also to be a choke coil.

The thermionic valve illustrated includes a so-called current rectifying wing or plate 5 preferably in the form of a wire electrode 18 which passes through the base end of the lamp bulb into proximity to the lamp filament but in a manner to be spaced apart therefrom. As illustrated, this electrode is 10 within the bulb but the invention is not to be thus limited. This electrode is here shown as taking part in rectifying the current, but it is not to be limited to this use. The outer end of the electrode is connected to a 15 binding post 19 which is mounted upon but insulated from the lamp base 3. This binding post has a binding screw 20 which may have clamping engagement with a circuit wire 21 passed through a hole in the binding post. Another binding post 22 is mounted upon and electrically connected with the lamp base 3 so as to be electrically united with the lamp contact 5 and with the rheostat which is also electrically united with 20 this contact through the intermediation of the lamp base 3, as has been described. The binding post 22 is provided with a binding screw 23 which may have clamping engagement with a circuit wire 24 passed through 25 a hole in this binding post. The two circuit wires 21 and 24 may be included in a flexible cord 25 which leads to the balance of suitable receiving apparatus, such as that diagrammatically indicated at the lower 30 ends of said wires, there being illustrated a telephone receiver 26 and an adjustable inductance 27 in series with the wires and also a condenser 28 in shunt of the receiver. The electrode 18 is desirably more intimately 35 associated with one leg of the filament 1 than with the other and means are provided whereby the leg of the filament with which the electrode is more intimately associated may be connected with the ungrounded side of the system. To this end the lamp structure is provided with a plug 40 45 that carries the lamp and whose lighting socket contact engaging contacts 30 and 31 are respectively formed with extensions 33

and 32 that are in the shape of sleeves into each of which either of the prongs 4 and 5 are insertable. The contact prong 4 upon the base of the lamp should be connected with the ungrounded side of the system. If the shell contact of the lamp socket receiving the plug 29 should happen to be connected with the ungrounded side of the system the lamp is inserted as illustrated, but if the butt contact of said socket is the one which is connected with the ungrounded side of the system then the position of the lamp should be reversed so as to bring the contact 4 into connection with the extension 33 of the contact 30 and the contact 5 in connection with the extension 32 of the contact 31.

While the contacts 4 and 5 are preferably carried by the lamp base, I do not wish to be limited to this arrangement.

While I have herein shown and particularly described the preferred embodiment of my invention I do not wish to be limited to the precise details of construction shown as changes may readily be made without departing from the spirit of my invention, but—

Having thus described my invention I claim as new and desire to secure by Letters Patent the following:—

1. A thermionic valve including a bulb containing a looped conductor inclusive of a filament and having terminal contacts connected with said conductor, these contacts constituting the input terminals of the valve; and an electrode adjacent the looped conductor and closer to one leg thereof than the other.

2. A thermionic valve including a looped conductor inclusive of a heating element and having terminal contacts connected therewith, these contacts constituting the input terminals of the valve; and an electrode adjacent the looped conductor and closer to one leg thereof than the other.

In witness whereof, I hereunto subscribe my name this ninth day of November, A. D., 1922.

HARRY O. RUGH.
